UNITED STATES PATENT OFFICE.

WILLIAM T. SMITH, OF PHILADELPHIA, PENNSYLVANIA.

WOVEN FABRIC.

No. 825,163.

Specification of Letters Patent.

Patented July 3, 1906.

Application filed March 17, 1905. Serial No. 250,618.

To all whom it may concern:

Be it known that I, WILLIAM T. SMITH, a citizen of the United States, residing in Philadelphia, Pennsylvania, have invented certain Improvements in Woven Fabrics, of which the following is a specification.

The object of my invention is to produce at a small fraction of the cost of an oriental rug or carpet a fabric closely resembling the same and constituting a cheap and acceptable substitute therefor. This object I attain in the following manner, reference being had to the accompanying drawings, in which—

Figure 1 represents an exaggerated section of a piece of fabric made in accordance with my invention, this section being taken in the direction of the warp; and Fig. 2 is a transverse section of the same—that is to say, a section taken in the direction of the weft.

An ordinary oriental rug or carpet consists of separate knots or tufts independently secured in position upon a supporting-warp, so that the face of the rug presents a projecting pile, while the back of the rug shows a pattern corresponding to that of the face, but of a less pronounced character, owing to the exposure or partial exposure of the loops or bights of the knots or tufts whose projecting ends constitute the pile-surface.

My improved fabric has a pile-surface composed of "one-sided" chenille, a packing composed of heavy weft-threads, interposed separator warp-threads, and tying warp-threads, whereby the chenille weft-threads of the face and the backing weft-threads are confined to said separator warp-threads, and said fabric can be woven in a power-loom, and hence can be produced much more cheaply and expeditiously than an ordinary oriental carpet or rug fabric.

By "one-sided" chenille I mean a chenille in which the tufting or pile-threads all project in one direction from a core or other support as distinguished from a round chenille from which the pile-threads or tufts project in all directions. Such chenille is employed in the form of a party-colored strip, the character of the coloring and the disposition of the colors in the strip depending upon the desired pattern to be produced in the finished fabric, such party-colored chenille strip being introduced as a weft-thread by means of a shuttle in the same manner as in weaving an ordinary yarn.

In the drawings, 1 represents the one-sided

chenille-surface weft-threads; 2, the heavy-backing weft-threads, which may be composed of cotton, jute, or other cheap material; 3, the separator warp-threads, and 5 the tying warp-threads, which are so shedded as to pass over the cores of the chenille weft-threads 1, thence down between successively-introduced backing weft-threads 2, and thence beneath said backing weft-threads, as shown in Fig. 1. As a consequence of this method of weaving the loops or bights of the chenille weft-threads are drawn down to a greater or less extent into the spaces between the backing weft-threads 2, so as to be visible from the back of the fabric in somewhat the same way as the loops or bights of the pile-knots or tufts of an oriental carpet or rug fabric.

Each set of warp-threads may comprise a pair of separator warp-threads 3, and either a single-binding warp-thread 4 or a plurality of such binding warp-threads, and the separator warp-threads and binding warp thread or threads of each set may pass through the same space of the reed or the binding warp thread or threads may pass through a different space of the reed from that which receives the separator warp-threads.

Preferably a binding warp-thread is disposed between a pair of separator warp-threads, as shown in Fig. 2 of the drawings, although said binding warp-thread may be at one side of the pair of separator warp-threads, or where a plurality of binding warp-threads are employed there may be one at each side of said pair or one at each side of the pair and one between the pair.

Having thus described my invention, I claim and desire to secure by Letters Patent—

95

1. A woven fabric in which are combined backing weft-threads, a pile-face consisting of weft-threads of one-sided chenille, separator warp-threads interposed between said face and back weft-threads, and binding warp-threads passing over said chenille-face weft-threads and under and between successive backing weft-threads, whereby the bights or loops at the back of the chenille-face weft-threads are drawn down between successive weft-threads of the backing so as to be visible on the back of the fabric, substantially as specified.

2. A woven fabric in which are combined backing weft-threads, a pile-face consisting

of weft-threads of one-sided chenille, separator warp-threads interposed between the face and back weft-threads, and binding warp-threads passing over said chenille-face weft-
5 threads and under and between successive backing weft-threads, whereby the bights or loops at the back of the chenille-face weft-threads are drawn down between successive weft-threads of the backing so as to be visible
10 on the back of the fabric, each binding warp-

thread being disposed between a pair of separator warp-threads, substantially as specified.

In testimony whereof I have signed my name to this specification in the presence of two subscribing witnesses.

WILLIAM T. SMITH.
